UNITED STATES PATENT OFFICE.

AUGUST W. BATCHER, OF HOQUIAM, WASHINGTON.

CARTRIDGE.

1,196,200.

Specification of Letters Patent. Patented Aug. 29, 1916.

Application filed April 28, 1915. Serial No. 24,403.

To all whom it may concern:

Be it known that I, AUGUST W. BATCHER, a citizen of the United States, residing at Hoquiam, in the county of Chehalis and State of Washington, have invented certain new and useful Improvements in Cartridges, of which the following is a specification:

This invention relates to cartridges for shot-guns; and its object is the perfecting of such devices to render the same more generally useful and capable of withstanding the effects of weather, and maintaining the contained ammunition in a dry and serviceable condition.

The invention consists in the novel construction and adaptation of parts, as will be hereinafter described, and claimed.

In the accompanying drawings, Figure 1 is a longitudinal sectional view of a cartridge embodying the present invention and shown in the form now preferred by me. Fig. 2 is a similar view of a modified form.

As illustrated in Fig. 1, I construct a cartridge which is formed of a metal outer casing having a cylindrical wall 5 and a closed end 6 which is centrally pierced for the reception of the fulminating holder 7. The cylindrical wall 5 of said casing is interiorly lined by means of a tube 8 of paper or an equivalent and at the inner end thereof is the usual annular packing piece 9.

A charge of powder or other explosive material, indicated by 10, is then put into said liner and retained by a wad 11. Upon the latter are deposited the projectiles or shot 12 and thereagainst is placed a closure or wad comprising a layer 13 of flexible metallic material, such as tin-foil, interposed between two layers 14 and 15 of pasteboard. The outer extremities of the casing wall 5 and of the liner-tube 8, denoted by

broken lines 5¹ and 8¹, are then turned inwardly to have their ends abut the outer layer 15 of said wad and thereby furnish a shoulder by which the wad is prevented from being accidentally displaced.

The cartridge shown in Fig. 2 is constructed as above explained, except that the casing and its liner are formed of a bottle-like configuration instead of cylindrical.

In the manufacture of the herein-described cartridges the paper or other suitable material which may be substituted therefor for the liner and wad, is saturated in hot paraffin to make the same impervious to water and which, with the metal layer 13 of the wad, renders the cartridge waterproof, which is an important advantage to the sportsman.

Another advantage is that by employing a metal casing for the entire length of the cartridge, the latter is not liable to become punctured or distorted and can be made to better fit within the barrel of a gun.

The turning in of the shell or casing against the wad also serves to resist or temporarily obstruct the ejection of the projectiles so that a greater velocity of discharge is attained.

What I claim as my invention, is—

In a cartridge, the combination with a shell having a metal casing, of a wad for retaining the charges of powder and shot within the shell, said wad being formed of alternating layers of tin-foil and paper to afford a stopper which is impervious to water.

Signed at Seattle, Washington, this 9th day of April, 1915.

AUGUST W. BATCHER.
